UNITED STATES PATENT OFFICE.

MAXYMILIAN J. MYSZKER, OF BUFFALO, NEW YORK.

GAS-VALVE.

1,218,299.

Specification of Letters Patent.

Patented Mar. 6, 1917.

Application filed October 10, 1914. Serial No. 866,117.

To all whom it may concern:

Be it known that I, MAXYMILIAN J. MYSZKER, a citizen of the United States, residing at Buffalo, in the county of Erie and State 5 of New York, have invented certain new and useful Improvements in Gas-Valves, of which the following is a specification, reference being had therein to the accompanying drawings.

10 This invention relates to gas valves and has for its object the production of a simple and efficient means for sounding an alarm when the gas pressure is reduced.

Another object of this invention is the 15 production of a simple and efficient actuating means for sounding the alarm after the pressure of the gas falls to a certain point.

With these and other objects in view this invention consists of certain novel combinations, 20 constructions, and arrangements of parts as will be hereinafter fully described and claimed.

In the accompanying drawings:—

Figure 1 is a side elevation of the device 25 showing the electrical wiring connection in diagram.

Fig. 2 is an end view partly broken away showing the valve casing.

Fig. 3 is a section taken on line 3—3, of 30 Fig. 1.

Fig. 4 is a vertical transverse section through the casing adapted to contain the main supply valve, showing the actuating means carried thereby.

35 Fig. 5 is a section taken at right angles to Fig. 4 through the main supply valve casing.

Fig. 6 is a vertical section taken on line 6—6, of Fig. 1.

Fig. 7 is a perspective view of the circuit 40 closing mechanism carried by the valve casing.

Fig. 8 is a section taken on line 8—8, of 45 Fig. 2.

Fig. 9 is a perspective view of the circuit closing member adapted to be actuated by the gas control valve.

Fig. 10 is a perspective view of the indicating hand used in connection with the main supply valve.

50 Fig. 11 is a section taken on line 11—11, of Fig. 1.

By referring to the drawings it will be seen that 1 designates the main supply valve casing through which passes the main supply pipe 2 having a rotating valve 3 placed

therein, which valve 3 is operated by a valve operating stem 4.

A spring carrying shaft 5 is connected to the valve stem 4 and carries a coil spring 6 and also a ratchet wheel 7, which ratchet wheel is normally held in a set position by the pawl 8 carried by the shaft 8'. The armature arm 9" is engaged by the armature 9' when this armature 9' is drawn into engagement with the electro-magnets 9 when 65 these magnets are energized by the closing of a circuit to be hereinafter set forth. When the armature arm is swung by the armature 9' the shaft 8' will pivot so as to swing the pawl 8 from engagement with the 70 ratchet wheel 7, thus allowing the shaft to be rotated by the spring for cutting off the flow of gas through the valve 30, as clearly disclosed in my prior application, filed October 16, 1913, Serial Number 795,607. 75

The shaft 5, however, carries an indicating hand 10 which may be removed therefrom when it is desired to wind the spring 6, and a detachable thumb nut 11 is mounted upon the shaft 5 for the purpose of facilitating the rotation of the shaft 5. 80

A contact bracket 12 is supported upon the main valve casing 1 and is insulated therefrom, and this bracket 12 is provided with a projecting finger 13, which finger is 85 adapted to be engaged by the indicating hand 10 when said hand is swung and makes contact therewith. The operation of the indicating hand 10 will be more clearly hereinafter described. 90

The gas supply pipe 2 supports an automatic valve containing casing comprising a metal base 14 upon which is supported the glass cylinder 15. A metal cover 16 is supported upon the glass cylinder 15 and constitutes a closure for the upper end thereof. A connection post supporting bar 17 is connected to the metal base of the casing 14 and carries a contact post 18 to which is connected the top 16. This top 16 is also 100 connected to the electro-magnetic means 9 by means of the wire 19 for actuating the same in conjunction with the mechanism to be hereinafter described. 95

The gas supply pipe 2 is provided with 105 an upwardly extending portion 20 in which is formed a discharge aperture 21. A slidably mounted cap 22 is mounted in the upper end of the pipe 20 and is also provided with an aperture 23 which is adapted to 110

register with the aperture 21 to allow the gas to escape into the casing and then pass out through the pipe 25 to the burner 24.

The cap 22 is provided with an outwardly projecting arm 26 having an off-set end 27, which off-set end travels in a longitudinally slotted member 28 as is clearly illustrated in Fig. 2. This longitudinally extending slotted member 28 is carried by a shaft 29, which shaft is journaled in a bearing 30 carried by the cover 16 of the cylinder 15. A contact plate 31 is carried by the shaft 29 as the cap 22 moves downwardly to the position shown in dotted lines in Fig. 2, the apertures 21 and 23 will move out of registration and prevent the passage of gas therethrough, and this downward movement of the cap will swing the contact member 31 to the position shown in dotted lines after first having caused the contact member 31 to form an electrical contact with the pivoted contact flap 32. A supporting post 33 is carried upon a supporting plate 34, and this supporting post 33 carries a bracket 35 having a binding post 36 to which the wire 37 is connected. The bracket 35 is provided with an upwardly extending portion 38. The bracket 41 is mounted upon the bracket 38, as shown in Fig. 8, and the screw 40 formed upon the bracket 41 supports a hanger bracket 39. The screw 40 carries a sleeve 42 upon which is supported a depending contact wire 43 which is adapted to be engaged by the off-set arm 44 of the crank 45, which crank supports the contact flap 32 above described. The wire 37 is also connected to the batteries 50 which are in turn connected to the electromagnetic operating means for actuating the valve 3 by means of the wire 54.

A bell circuit is also employed in connection with the present electrical mechanism which comprises a wire 55 connected to the wire 37 which is connected to the battery 50. The wire 55 is connected to a bell or other suitable signal 56, and this bell is connected to the bracket 12 by means of a wire 57. The operation of the present device is as follows:

When the gas is at its normal pressure the cap 22 will be held in the position shown in Fig. 1, thereby allowing the apertures 21 and 23 to register. After the pressure of the gas, however, falls below the pre-determined point, the cap 22 will drop and close the passage-way between the apertures 21 and 23, and cause, at the same time, the plate 31 to swing to the position shown in dotted lines caused by the off-set arm 27 traveling in the longitudinally extending slotted member 28.

As the contact member 31 comes in contact with the flap 32, the electric current will pass from the battery 50 through the

wire 37, through the bracket 38, through the depending wire 43, through the crank 45, through the heap 32, through the contact plate 31, through the top of the casing 16, through the wire 19, through the magnetic operating means 9, through the wire 54, and then through the battery 50, thereby actuating the magnetic means 9 for operating the valve carried by the pipe 2.

It should be understood that simultaneous with the operation of the circuit just described a current will pass from the battery 50 through the wire 55, through the bell 56, through the wire 57, to the contact point 13, through the arrow 10, through the wire 10^a to the wire 54 and then to the battery 50.

From the foregoing description it will be seen that a very simple and efficient means has been produced for automatically cutting off the flow of gas to prevent the accidental escape of the gas after the light has been extinguished due to the falling of the pressure of the gas supply.

Having thus described the invention what is claimed as new, is:—

1. In a device of the class described, the combination of a gas supply pipe, a casing carried by said pipe, a burner pipe leading from said casing, a movable cap carried by said first-mentioned pipe, an arm extending from said cap, a shaft revolvably mounted upon said casing, a longitudinally slotted member carried by said shaft, said arm extending through said member, a contact plate fixed upon said shaft, said cap being adapted to be moved by gas pressure within said supply pipe, whereby said shaft will be rocked so as to swing said plate, and means carried by said casing, and coöperating with said plate for closing an electric circuit.

2. In a device of the class described, the combination of a gas chamber, a shaft carried by said chamber, means for turning said shaft when gas pressure within said chamber decreases, a plate carried by said shaft, a bracket carried upon and insulated from said chamber, a contact wire carried by said bracket, an insulated hanger bracket carried by said first-mentioned bracket, means electrically connected to said chamber and said wire, a crank pivotally mounted upon said hanger bracket, a flap fixed upon said crank, said plate being adapted to swing into said flap as said shaft is rotated, whereby said crank will be turned into engagement with said wire for closing a circuit.

3. In a device of the class described, the combination of a gas chamber, a shaft carried by said chamber, means for turning said shaft when gas pressure within said chamber decreases, a plate carried by said shaft, a bracket carried by and insulated from said chamber, a bolt carried by said bracket, a wire carried by said bolt, an insulated

- hanger bracket carried by said bolt, said hanger bracket having an inverted U-shaped lower portion, a crank pivotally supported by said U-shaped portion, a flap carried by 5 said crank within said U-shaped portion and depending therebelow, means electrically connected to said chamber and said wire, said plate being adapted to swing into engagement with said flap as said shaft is 10 rotated, whereby said flap will swing said crank into engagement with said wire for closing a circuit.
4. In a device of the class described, the combination of a gas supply pipe, a casing 15 carried by said pipe, a burner pipe leading from said casing, a movable cap carried by said first-mentioned pipe, an arm extending from said cap, a shaft revolvably mounted upon said casing, a longitudinally slotted 20 member carried by said shaft, said arm extending through said member, a contact plate fixed upon said shaft, said cap being adapted to be moved by gas pressure within said supply pipe, whereby said shaft will be 25 rocked so as to swing said plate, a bracket carried by and insulated from said casing, a bolt carried by said bracket, a wire carried by said bolt, an insulated hanger bracket carried by said bolt, said hanger bracket having an inverted U-shaped lower portion, 30 a crank pivotally supported by said U-shaped portion, a flap carried by said crank within said U-shaped portion and depending therebelow, means electrically connected to said casing and said wire, said 35 plate being adapted to swing into engagement with said flap as said shaft is rotated, whereby said flap will swing said crank into engagement with said wire for closing a circuit. 40
5. In a device of the class described, the combination of a gas chamber, a shaft carried thereby, means for turning said shaft, operated by fluid pressure within said chamber, and circuit closing means outside said 45 chamber operated by said shaft.

In testimony whereof I hereunto affix my signature in presence of two witnesses.

MAXYMILIAN J. MYSZKER.
